THOMAS F. CALDWELL, OF CARLSTADT, NEW JERSEY, ASSIGNOR TO THE FLINTKOTE COMPANY, OF BOSTON, MASSACHUSETTS, A CORPORATION OF MASSACHUSETTS.

SHEET-GUIDING DEVICE FOR SATURATING TANKS.

Application filed December 24, 1919. Serial No. 347,220.

To all whom it may concern:

Be it known that I, THOMAS F. CALDWELL, a citizen of the United States, residing at Carlstadt, in the county of Bergen and State of New Jersey, have invented new and useful Improvements in Sheet-Guiding Devices for Saturating Tanks, of which the following is a specification.

This invention has relation to apparatus for treating fabrics, such for example as impregnating paper felt with a waterproofing compound in the manufacture of prepared roofing. In such manufacture, the asphalt or other bituminous compound is contained in a tank, and, when it is in a molten or liquid condition, the felt sheet is drawn through it, so as to absorb the hot molten material in the pores or interstices thereof. According to the materials of which it is made and other conditions surrounding its production, the felt varies in its absorbent characteristics, and consequently the length of time in which it is immersed in the impregnating compound must be increased or decreased, in order that standard roofing felt carrying a predetermined percentage of the compound may be produced. This period of immersion may likewise depend upon the viscosity of the impregnating compound. The period of immersion of the fabric in the compound may be varied by increasing or decreasing the speed of its travel therethrough, or it may be varied by increasing or decreasing the length of the immersed portion of the fabric, i. e. that portion which at any one time is passing through the compound. There are serious objections to greatly varying the speed of travel of the sheet, since decreasing the speed effects a decrease in production, in addition to slowing down the other instrumentalities which operate upon the saturated or impregnated sheet. It follows then that optimum results (all other things being equal) may be obtained by varying the length of the immersed portion of the fabric.

Heretofore it has been the practice to thread or pass the fabric under rolls or guides located below the level of the com-

pound in the saturating tank, and this operation is a difficult and a dangerous one, where the impregnating compound is heated to a high temperature or contains materials liable to affect the health or well being of the operatives. Paper felt of the nature of that employed in the manufacture of prepared roofing, because of the necessity of having it highly porous and absorbent, does not possess great tensile strength, and, in the practical manufacture of such roofing, it sometimes happens that the felt is parted and must be rethreaded through the vat or tank.

The present invention has for its object to provide a saturating tank with guiding means for the sheet, which may be withdrawn from the tank far enough to permit the sheet to be threaded or passed around them, and then be immersed in the contents of the tank, so as to cause the sheet thereafter to travel through the saturating compound. Another object of the invention is to provide some means for varying the period of time in which any given portion of the traveling fabric is immersed in the bath of compound, without varying the speed of travel of the fabric.

On the accompanying drawings is illustrated an apparatus embodying the invention, which will hereinafter be described in detail.

Figure 1 represents a side elevation of the apparatus, the tank being broken off at its ends.

Figure 2 represents a transverse vertical section on the line 2—2 of Figure 1.

I have not shown the instrumentalities by which the sheet is drawn or caused to travel through the tank, nor the squeeze rolls by which the surplus compound is removed from the impregnated sheet, as these are well known and form no part of the present invention. It suffices to say that the sheet-feeding instrumentalities are intended to cause the sheet to travel at a uniform speed, and may be stopped and started at the will of the operative, but of course the speed may be varied if desired.

The tank is indicated at 10, being of the requisite length, width and depth, and, when the saturant is asphalt or is of a bituminous or resinous nature, is provided with means 5 for heating the saturant and maintaining it at the high temperature necessary to ensure a relatively low viscosity. Near the ends of the tank are guide rolls 11, 12, which are preferably above the level of the saturating compound indicated by the dotted line $a-a$. The sheet of felt is indicated at 13, and it is looped about suitable guides 14, 15, 16 and 17, which with convenience may be formed as rolls. These guides are so arranged that 10 those at 14, 16, and those at 15, 17, may be bodily adjusted toward and from each other to vary the distance between them, and thus to vary the lengths of the loops of the sheet. Moreover, all the rolls may be vertically adjusted to immerse them in and withdraw 15 them from the body of the saturant. The rolls 14, 16, are journaled in the lower ends of a pair of upright slides 18 which are movable in guides 19 afforded by standards 20 rigidly secured to the sides of the tank. 20 Each slide is formed as or provided with a rack 21, and meshing with the racks are pinions 22 fast upon a shaft 23. Said shaft is journaled in bearings afforded by the standards 20, and is provided at one or both ends with a hand wheel 24 by which it may be rotated in either direction.

The rolls 15, 17, are likewise mounted in upright slides 25, movable in guides 26 (similar to those at 19) afforded by upright standards 27. In this case, however, the standards are not fixed to the sides of the tank but are gibbed to slide on horizontal guideways 28 extending longitudinally of 30 and secured to the sides of the tank. A shaft 29 journaled in the upper ends of the standards 27 has pinions 30 meshing with racks 31 formed on or secured to said slides 25, and a hand wheel 32 by which it may be rotated. The standards 27 constitute a longitudinally movable carriage, which is fed lengthwise of the tank, toward and from the fixed standards 20, by a shaft 33 having pinions 34 meshing with racks 35 secured to 35 the tank. A hand wheel 36 on the shaft 33 affords means by which it may be rotated to effect the movement of the carriage and the guides 15, 17, supported thereby.

When it is desired to introduce a new 40 sheet of fabric into the apparatus, the shafts 23 and 29 are rotated by means of their respective hand wheels to move the slides upwardly until the sheet guides supported thereby are above the level of the saturating compound. The sheet is then looped back and forth around the guides 14, 15, 16, 17, as shown, to form the bights 12^a, 12^b, 12^c, after which the slides are depressed to immerse the guides and the bights in the sat-

urant. The sheet, as shown, enters the bath 65 of saturating compound at the point indicated at 40, and, after passing around the guides, emerges at a corresponding point, between the guide 17 and the guide 11, so that, during the travel of the sheet, a predetermined length thereof is in constant immersion. Should it be found that the sheet, because of its texture or of the viscosity of the compound, is not absorbing the desired amount of the compound, the guides 15, 17, 70 75 may be further spaced or separated from the guides 14, 16, so as to increase the length of the fabric immersed in the saturant, and the duration of the immersion of each part of the fabric. On the other hand, the guides 80 may be brought nearer together, when occasion requires, to shorten the period of immersion and the length of fabric submerged in the compound at any one time.

Of course, the number of guides which are 85 supported by the slides or carriers 18, 25, may be varied as desired.

It is evident that the invention, as defined in the claims, is capable of many different embodiments. I desire to have it understood 90 that I have not attempted to show the parts of the apparatus, as herein described, in their relative sizes or dimensions, and that the phraseology herein employed is for the purpose of description and not of limitation. 95

Having thus explained the nature of my said invention and described a way of making and using the same, although without attempting to set forth all of the forms in which it may be made or all of the modes of 100 its use, what I claim is:

1. Sheet treating apparatus comprising a tank for containing a body of liquid saturating compound, a pair of spaced carriers, guide rollers carried by each carrier and about which sheet material may be looped between said carriers, means for moving said carriers toward and from each other to vary the length of material passing about said rollers, and means for independently 105 raising said carriers to bring said rollers above the surface of the saturating liquid in said tank.

2. Sheet-treating apparatus comprising a tank for containing a body of liquid saturating compound, guides for a travelling sheet to guide the same through the saturating compound, spaced carriers for said guides, and means for moving one of said carriers toward and from the other. 115

3. Sheet-treating apparatus comprising a tank for containing a body of liquid saturating compound, guides for a travelling sheet to guide the same through the saturating compound, means for moving said guides one in reference to the other to increase the length of fabric undergoing immersion in the compound, and means for bodily ele- 120 125

vating said guides to a plane above the level of the compound, to facilitate passing a sheet around said guides.

4. Sheet treating apparatus comprising a tank for containing a body of liquid saturating compound, guides, a pair of spaced carriers for said guides, means for independently raising and lowering said carriers to

immerse their respective guides in or raise them from said body of liquid, and the means for moving one of said carriers bodily toward and from the other of said carriers.

In testimony whereof I have affixed my signature.

THOMAS F. CALDWELL.
